UNITED STATES PATENT OFFICE.

RALPH H. KORN, OF NEW YORK, N. Y.

CARRIAGE FOR ARTILLERY.

1,308,286.

Specification of Letters Patent.

Patented July 1, 1919.

Application filed March 25, 1918. Serial No. 224,535.

To all whom it may concern:

Be it known that I, RALPH H. KORN, a citizen of the United States, and resident of the city of New York, in the county of 5 New York and State of New York, have invented certain new and useful Improvements in Carriages for Artillery, of which the following is a specification.

This invention relates to improvements 10 in carriages for artillery and is directed particularly to a novel and advantageous construction of gun carriage.

The objects of this invention are to provide a gun carriage of the character described which is light and portable so that it may be easily moved from place to place. Being thoroughly mobile, this carriage makes it possible to advance or retire the gun as desired, so that the gun can be used 15 in line with, in advance of, or in support of, either advancing, retiring, or stationary infantry; to provide the same with means for protecting the operator from enemy fire and with further means whereby ammunition 20 for the gun may be carried on the carriage; to so construct the carriage as to enable one to readily mount and dismount it so that the parts may be packed compactly for shipment; and to provide a carriage 25 with means for a machine or other type of gun now in use. The whole construction is light and strong and yet comparatively inexpensive to manufacture.

Further objects and advantages of this 30 invention will appear from the detailed description and the features of novelty will be particularly pointed out in the claims.

The carriage embodies a frame work preferably formed of tubular elements and a 35 shield of metal or other suitable material mounted thereon. The shield is provided with an opening through which the barrel of a machine or other type of gun can be projected and sighted, and ammunition can 40 be carried in a proper receptacle in the frame.

Referring to the drawings which form a part of this specification,

Figure 1 is a rear view of my improved 45 carriage;

Fig. 2 is a side elevational view of the same;

Fig. 3 is a cross sectional view taken along 50 line $\alpha-\alpha$ of Fig. 1 showing the means used 55 to embrace and hold the tubes together

where the members cross in forming the frame;

Fig. 4 is a fractional view of the apex of the frame showing means for holding flattened ends of the members together and 60 also for mounting the swivel elements on which the gun swings;

Fig. 5 is an exterior view of a portion of the frame illustrating the use of the brace elements which permit the members to retain their circular cross section and be more thoroughly braced than would be the case were the members flattened at the junction points; and

Fig. 6 is a side view of the frame portion 70 indicated by line $\alpha-\alpha$ of Fig. 1.

Referring in detail to the drawing, the frame consists of the pairs of tubes A, A', B, B' and C, C', suitably braced and joined together as shown in the drawing. The 75 tubular members A and A' are provided at one end with a handle A² and the opposite ends form a portion of the axle bearing of the wheel D as shown at $a-a$. The tubes B, B' form the front portion of the frame 80 and extend down from the apex thereof to also form a portion of the axle bearing, as will be clear from the drawing. The wheel D is held between the ends of the tubes A, A' and B, B' in a manner similar 85 to that of the ordinary wheel-barrow. As will be clear from the drawing one end of the tubes C, C' serve as feet for the frame while the opposite ends are flattened to be held at the apex by means of the bolt E. 90

The shield is held to the frame in any suitable manner as by means of straps shown in dotted lines in Fig. 2 and indicated by F, F, etc., and has an opening F' therein through which the gun F² is projected and sighted. 95 The strap G is formed to fit the contour of the gun and has a depending cylindrical portion G' which fits in a socket H' formed in the element H which is held in the frame by the bolt I. A universal joint is thus provided whereby the gun can be turned at 100 right angles to the frame, and also be swiveled on the bolt I to be elevated or depressed.

In Fig. 3 I have shown means whereby 105 the tubular elements of the frame may be held together and suitably braced and spaced apart without being flattened at junction points so as to provide a strong and rigid construction. The tubes A, A' and 110

B, B' are there shown held together in spaced relation by means of a long bolt J passing through the sleeve member K, K', K² having their ends cut out to conform 5 to the contour of the tubes as will be clear from Fig. 5. To space the tubes A and B and A' and B', I provide the space blocks L curved to conform to the contour of the tubes and perforated to permit the bolt to 10 pass therethrough. These blocks L serve further to brace the tubes and thus strengthen the frame. An ammunition box M may be secured in any suitable manner to the frame as by means of the straps N.

15 It will thus be clear that I have provided a gun carriage extremely simple in construction, light and portable so that it may be easily wheeled manually from place to place by a single person, adapted to carry any 20 type of gun in use, and furthermore easily assembled or disassembled for shipment.

Having thus described my invention, I claim as new and desire to secure by Letters Patent:

25 1. A gun carriage comprising a frame, a wheel carried at the lower end thereof, said frame consisting of a plurality of members joined together, said members being joined to form an apex, a pair of said members 30 being bent and positioned to form handles and several of said members extending down to the base of the frame to provide an axle bearing for the carriage wheel, and means swiveled at the apex for mounting a gun.

35 2. In a gun carriage, a frame, a wheel carried at the lower end thereof, said frame comprising three pairs of members, one of said pairs forming a stand or base for the carriage, another of said pairs joined to said 40 first mentioned pair and bent at one end to

form handles and extending down to the base of the frame to form the axle bearing for the carriage wheel, and the third pair extending down to the base to coöperate with said last mentioned pair in forming 45 the axle bearing and extending upward to coöperate with the first mentioned pair of members to form the apex of the frame.

3. In a gun carriage, a frame, a wheel carried at the lower end thereof, said frame 50 comprising three pairs of members, one of said pairs forming a stand or base for the carriage, another of said pairs joined to said first mentioned pair and bent at one end to form handles and extending down to the 55 base of the frame to form the axle bearing for the carriage wheel and the third pair extending down to the base to coöperate with said last mentioned pair in forming the axle bearing and extending upward to 60 coöperate with the first mentioned pair of members to form the apex of the frame, and means swiveled at the apex for mounting the gun.

4. In a gun carriage, a frame construction comprising a plurality of members joined and braced by means permitting said members to retain their circular cross section at the joints, a wheel located at the lower end of said frame, handles on said 70 frame and a shield on the front thereof having an opening therein for the purpose specified.

Signed at New York in the county of New York and State of New York this 22nd day 75 of March A. D. 1918.

RALPH H. KORN.
